UNITED STATES PATENT OFFICE

EDMOND FRANÇOIS LÉOPOLD VAGNEUX, OF PARIS, FRANCE

SECURING MEANS FOR REINFORCED-CONCRETE SLEEPERS

Application filed May 27, 1930, Serial No. 456,223, and in France December 14, 1929.

A commonly used device for securing to reinforced concrete sleepers consists in using a wooden plug or block fitted in the concrete for screwing therein a coach screw or bolt. For suitably anchoring to the sleeper it is necessary for the plug or block to show sufficient resistance against withdrawal, loosening and bursting when the coach screw or bolt is being screwed therein.

- 10 In the wooden plugs or blocks used heretofore resistance against bursting is generally provided through the wedging of one end of the said plug or block inside the concrete which binds thus only the said end.
- 15 Moreover nothing prevents water from passing through the cracks which might exist or arise in the wooden plug or block.

My invention has for its object to remove these drawbacks. In the device to be described hereinafter, the wooden plug or block wherein the coach screw or bolt is screwed is bound by the concrete at both ends which provides a reliable resistance of the wood against bursting.

- 25 Moreover the plugs or blocks when set in place are coated between their ends with an insulating putty which fills in the ends of the cracks in the wood.

To this end I give the recess in the concrete and the plug substantially similar shapes, widening slightly at their upper end so as to make the engagement of the plug easier. The difference between the recess and the plug resides in that the extreme end 30 horizontal cross-sections of the plug are slightly larger than the corresponding cross-sections of the recess, whereas the contrary is the case for the central cross-sections. Thus the plug being suitably engaged with friction inside its recess, is securely held therein through both ends whereas an empty annular space exists between the plug and recess towards the middle of their length.

- 40 I obtain thus an assembly similar to that shown diagrammatically in Fig. 1 wherein the plug is shown in full lines and the recess in dotted lines.

45 By way of example I have shown the cross-sections as oval whereby the plug ap-

pears with a shape similar to that of a tool handle.

It is of particular interest to give the plug the shape of a body of revolution whereby it is possible to secure it by screwing it into 55 a helical lining fitted in the concrete of the recess.

In this case I give the surfaces of the recess and of the plug the shape of surfaces of revolution the radii of the end sections of the 60 plug being larger than for the recess whereas the central part of the plug is slightly narrower than this recess so as to make the engagement of the plug easier and to provide the annular space mentioned hereinabove. 65 It is apparent from Fig. 2 that this means that the meridian lines 1 of the recess and 2 of the plug being brought to have the same axis and to end in the same cross-sections, they will intersect at two points 3 and 4. 70

Obviously in practice I give the curves 1 and 2 suitable simple shapes of which some will be described hereinbelow by way of example and shown on accompanying drawings.

75 Figs. 1 to 7 are diagrams,

Fig. 1 shows, as explained, the general shape of a plug and its recess,

Fig. 2 shows, also as explained, the general appearance of the meridian lines of the recess 80 and of the plug,

Figs. 3 and 4 are cross-sections through a meridian line of a double frustoconical plug and recess,

Fig. 5 shows the meridian lines of the preceding figures supposed to be plotted with the same axis and the same terminal bases,

Fig. 6 is a modification of the preceding device wherein the plug is a simple frustocone,

Fig. 7 is another modification wherein it is the recess which is frustoconical,

Fig. 8 illustrates a further modification wherein the plug is cylindroconical,

Fig. 9 shows in detail a plug according to the invention,

Fig. 10 the drill for recessing the sleepers,

Fig. 11 a rail secured through an ordinary coach screw,

Fig. 12 a rail secured through a bolt coach screw.

In the form of practice shown in Fig. 3, the inner surface of the recess comprises two superposed frustocones 5 and 6 having the same axis and connected along the parallel circles 11, the angle of the generating line of the upper frustocone 6 with the vertical being smaller than for the lower frustocone 5.

Fig. 4 shows the plug corresponding to this recess; it comprises two frustocones 8 and 9 connected along the parallel circles 11, the radius of which is smaller than that of the parallel circle 7; the radii of the upper and lower bases 12 and 13 are on the contrary larger than the corresponding bases of the recess; it is apparent from Fig. 5 which shows the meridian lines of the two preceding figures superposed and plotted with the same axis and the same bases that when the plug is forced into its recess its ends are compressed or, more exactly, bound by the concrete whereas at its central part there is an annular empty space 14 left between the plug and the concrete.

The shape of one of these elements may be simplified by using for it a simple cone as shown in Figs. 6 and 7. I may also replace one of the frustocones by a cylinder as shown in Fig. 8 where the plug is similar to that of Fig. 4 except in that the lower frustocone 8 is replaced by a cylinder 10.

The angles with the axis of the generating lines have been obviously grossly exaggerated on the above described diagrammatical figures. I have not shown either thereon the helical grooves provided in the recess and the plug.

On the contrary Figs. 9 and 10 show at a larger scale, a plug and the tool used for recessing the concrete. The plug illustrated in Fig. 9 comprises a lower cylindrical part 15 and above it a frustoconical part 16. It ends with an upper cylindrical part 17 which makes its insertion easier through the agency of a suitable tool. The drill used for shaping the recess comprises (Fig. 10) two frustoconical parts 18 and 19 disposed in a manner similar to those shown in Fig. 3 and shows an upper terminal cylindrical part 21 which allows an easier handling.

The plug is provided with a helical groove 21 and the drill shows also a groove 20 having the same pitch as the plug groove; in the drill groove I fit a steel helix 22 which is firmly held by the concrete when it has set and the drill body is removed through unscrewing.

Fig. 11 shows at the same scale the whole rail anchoring means. The rail 23 rests with the interposition of a wooden support 24 on the concrete sleeper 25. In this sleeper is provided in the formation thereof a recess through the agency of the above-described

drill. The plug 26 of the type shown in Fig. 9 is engaged therein after immersion thereof in a bituminous putty; it is held down by the helical steel part 27 which engages the grooves both of the plug and of its recess. It is apparent that the plug is securely bound by the concrete at both ends whereas the small empty annular gap 28 is filled with the bituminous putty which provides thus in a reliable manner for watertightness and hydraulic and electric insulation; I screw into the plug thus secured a coach screw 29 the upper end of which bears in the usual manner against the rail foot which it holds down.

Before securing the coach screw, the upper cylindrical end 17 of the plug is sawn off; it is however of advantage as shown in the figure to allow the wood to project on the side adjacent to the rail foot whereby it serves as an abutment which prevents any inclination of the coach screw collar.

Fig. 12 shows in a similar manner a rail held down by a coach-screw-bolt 29. In this figure and the preceding one the same reference letters designate the same parts.

In the making of the different parts, the drill and plugs are given a size such that the plugs may be engaged without difficulty until the screwing down is nearly at an end at which moment the parts are gradually tightened and the wooden plug is slightly compressed at both ends.

It is apparent that the plug resists perfectly stresses having a tendency to:

(a) Tear off the helical steel part,

(b) Cause a bursting of the plug which is prevented by the upper and lower binding,

(c) Unscrew the plug by reason of the said binding and of the adherence of the bituminous putty,

(d) Cause electric current leaks and entrance of moisture, owing to the filling in with putty of the cracks in the wood.

The anchorage through a coach screw bolt as shown in Fig. 12 is of course more satisfactory in the case of a wooden plug as the fastening stresses are effected on the bolt part and not on the coach-screw part. The coach-screw bolt has been secured once and for all in the wood and there is consequently no possible mechanical wear of the wood through the action of the coach-screw thread. The plug will remain in proper working order as long as its wood remains sound.

But if it is admissible to replace the plug as often as necessary i. e. as soon as it is ascertained that the coach screw becomes loose, the much simpler anchoring through an ordinary coach screw may be used.

What I claim is:

1. In anchoring means for rails on concrete sleepers, the combination of a vertically upwardly flaring recessed part in the concrete, a cooperating upwardly flaring

5 plug adapted to be engaged therein, the end horizontal cross-sections of which are slightly larger than those of the recess in the concrete part and the central horizontal cross-sections of which are slightly smaller than the corresponding cross-sections of said recess, and rail anchoring means adapted to be held in said plug.

2. In anchoring means for rails on concrete sleepers, the combination of a vertically upwardly flaring recessed part in the concrete, a cooperating upwardly flaring plug adapted to be engaged therein, the end horizontal cross-sections of which are 10 slightly larger than those of the recess in the concrete part and the central horizontal cross-sections of which are slightly smaller than the corresponding cross-sections of said recess, the recess and the plug being bounded 15 by surfaces of revolution the meridian lines of which are adapted when plotted with the same axes and the same terminal cross-sections to intersect twice and rail anchoring means adapted to be held in said plug.

25 3. In anchoring means for rails on concrete sleepers, the combination of a vertically upwardly flaring recessed part in the concrete, a cooperating upwardly flaring plug adapted to be engaged therein, the end 30 horizontal cross-sections of which are slightly larger than those of the recess in the concrete part and the central horizontal cross-sections of which are slightly smaller than the corresponding cross-sections of said 35 recess, one of the said flaring parts, recess or plug, having a surface formed of superposed frustocones connected along parallel circles and the other flaring part having a mere frustoconical wall and rail anchoring means 40 adapted to be held in said plug.

4. In anchoring means for rails on concrete sleepers, the combination of a vertically upwardly flaring recessed part in the concrete, a cooperating upwardly flaring plug adapted 45 to be engaged therein, the end horizontal cross-sections of which are slightly larger than those of the recess in the concrete part and the central horizontal cross-sections of which are slightly smaller than the corresponding cross-sections of said recess, a helical groove being provided in the wall of the plug, a helical part securely held in the concrete projecting beyond the recess wall and adapted to engage the groove in the plug, 50 and rail anchoring means adapted to be held in said plug.

5. In anchoring means for rails on concrete sleepers, the combination of a vertically upwardly flaring recessed part in the concrete, a cooperating upwardly flaring plug adapted 55 to be engaged therein, the end horizontal cross-sections of which are slightly larger than those of the recess in the concrete part and the central horizontal cross-sections of which are slightly smaller than 60

the corresponding cross-sections of said recess, an insulating bituminous putty impregnating the plug and adapted to fill the empty annular central space left free between the plug and the recess in the concrete and rail anchoring means adapted to be held in said 70 plug.

In testimony whereof I have affixed my signature.
